No. 36,781.

Patented February 9, 1904.

UNITED STATES PATENT OFFICE.

LEON BLOWER, OF NEW YORK, N. Y.

DESIGN FOR A DECANTER.

SPECIFICATION forming part of Design No. 36,781, dated February 9, 1904.

Application filed December 21, 1903. Serial No. 186,129. Term of patent 7 years.

To all whom it may concern:

Be it known that I, LEON BLOWER, a citizen of the United States, residing at 333 East Sixteenth street, New York, county of New York, 5 State of New York, have invented a certain new, original, and ornamental Design for a Decanter, fully described and represented in the following specification and the accompanying drawings, forming a part of the same.

10 In the drawings, which show my design,

Figure 1 is a perspective view of the decanter. Fig. 2 is an elevation of the decanter, and Fig. 3 is a cross-section on line 3 3, in Fig. 2.

What I claim is—

The ornamental design for a decanter as 15 shown.

LEON BLOWER.

Witnesses:

L. LEE,

THOMAS S. CRANE.
